CLAIM

We claim the ornamental design for a shoe frame, substantially as shown and described.

DESCRIPTION

FIG. 1 is a top front perspective view of a shoe frame embodying the design of the present invention;

FIG. 2 is a bottom rear perspective view thereof;

FIG. 3 is a front elevation view thereof;

FIG. 4 is a rear elevation view, thereof;

FIG. 5 is a left elevational view thereof;

FIG. 6 is a right elevational view thereof;

FIG. 7 is a top plan view thereof; and,

FIG. 8 is a bottom plan view thereof.

1 Claim, 5 Drawing Sheets
